UNITED STATES PATENT OFFICE.

AARON M. WEBER, OF OSHKOSH, WISCONSIN.

DESIGN FOR A HOOK.

SPECIFICATION forming part of Design No. 25,990, dated September 8, 1896.

Application filed June 22, 1896. Serial No. 596,550. Term of patent 14 years.

To all whom it may concern:

Be it known that I, AARON M. WEBER, a citizen of the United States, residing at Oshkosh, in the county of Winnebago and State of Wisconsin, have invented and produced a new and original Design for a Hook; and I do hereby declare the following to be a full, clear, and exact description of the same, reference being had to the accompanying drawings, forming a part thereof.

Figure 1 shows in top plan view a hook embodying my design. Fig. 2 is an edge view.

My design for a hook consists of the shape

substantially as shown, which shape comprises the straight bars or portions a' , bent upon themselves at a^3 , the straight bars or portions a^2 , and the laterally-enlarged triangularly looped portion a .

I claim—

The design for a hook, substantially as shown and described.

In testimony whereof I affix my signature in presence of two witnesses.

AARON M. WEBER.
